DESIGN FOR AN ELECTRIC MOTOR

Robert L. Drake, Piqua, Ohio, assignor, by mesne assignments, to Reconstruction Finance Corporation, Cleveland, Ohio, a corporation of the United States

Application February 25, 1942, Serial No. 105,977

Term of patent 14 years

To whom it may concern:

Be it known that I, Robert L. Drake, a citizen of the United States, residing at Piqua, in the county of Miami and the State of Ohio, have invented a certain new, original, and ornamental Design for Electric Motor, of which the following is a specification, reference being had to the accompanying drawing, forming part thereof, in which:

Fig. 1 is a perspective view of an electric motor showing my design;

Fig. 2 is a top plan view of the electric motor of Fig. 1.

The characteristic feature of my design resides in the electric motor disclosed having the specific centrally located series of projecting laminations as shown.

I claim:

The ornamental design for an electric motor, substantially as shown and described.

ROBERT L. DRAKE.
